UNITED STATES PATENT OFFICE

JEAN BOUNEAU, OF PARIS, FRANCE.

ELECTRIC FURNACE.

No. 926,236.

Specification of Letters Patent. Patented June 29, 1909.

Application filed July 17, 1907. Serial No. 384,218.

To all whom it may concern:

Be it known that I, JEAN BOUNEAU, a citizen of the French Republic, residing at Paris, in France, have invented certain new and useful Improvements in Electric Furnaces, of which the following is a specification.

This invention relates to improvements in electric blast furnaces.

10 The electric furnaces hitherto used give small efficiency considering the consumption of electric energy used for reducing the materials to be treated. The reason for this is that the mixture introduced into the furnace 15 is cold and that the arc has to maintain the reduced mass in fusion, till the full reaction of the charge is effected. Further the electrodes placed vertically endwise only reduced about a third of the charge submitted 20 to the action of the current in a crucible into the center of which the electrode passes; only that part, which is near the arc being reduced, while the other part undergoes but an incomplete transformation.

25 The above disadvantages are obviated by means of the present improvements which are shown in the accompanying drawings, in which:

30 Figure 1 is a longitudinal section of a blast furnace, provided with the improvements. Fig. 2 is a cross-section thereof and Fig. 3 a plan-view.

In all the figures the various parts are 35 designated as follows: *a*, the reaction-chamber; *b*, the shaft; *c*, manhole for the shaft *b*; *d*, the shaft inlet; *e*, horizontal electrodes; *g*, trolleys carrying the electrodes; *h*, tap hole; *l*, refining chamber; *m*, refining crucible; *o*, negative electrode of the positive 40 crucible; *p*, tap hole for the crucible *m*, *r* track for the trolleys *g*; *r*¹ branch track and *z* the uptake from shaft *b*.

The operation is as follows: The electrodes *e* carried by the movable trolleys *g*, *g*, 45 on the rails *r*, *r*, and moved by suitable mechanical means, are moved endwise into the furnace *a*. The charge is then inserted in sufficient quantity to cover the electrodes and the walls of the furnace *a*. The electrode *o* is placed in contact with the carbon

55 crucible *m*, and the inlet *d* and manhole *c* are closed in any known or suitable manner. By moving the trolleys and consequently the electrodes *e*, *e* away from one another, the arc is struck and the charge near the latter is infused and passes between the electrodes *e*, *e*, into the refining chamber *m* and out through tap hole *p*. When the reduction has 60 commenced a further charge is inserted sufficient to nearly fill the shaft *b* in order that the heat and reaction gases in passing to the uptake *z* may pass through the mixture and heat same. When sufficient fused mass has 65 accumulated in the crucible *m*, the electrode *o* may be raised and the arc formed maintains said mass in fusion. The electrode *o* being placed in proximity to the running tap hole *p* compels the reduced material to undergo the action of the arc a second time before discharge and thus cause it to be cleared 70 of impurities which pass between the electrodes *e*, *e*. The operation is continuous and when the electrodes *e*, *e* are consumed they are removed from the furnace and replaced by others which may be mounted on trolleys 75 on the branch track *r*¹.

If desired, the manhole *c* may serve for the introduction of the preliminary charge in order to permit agitation of the charge in case of need, and to follow the course of the 80 reaction.

What I claim as my invention and desire to secure by Letters Patent of the United States is:—

1. An electric furnace comprising a reaction chamber, a shaft above the same and in communication therewith, said shaft having a sloping floor almost separating it from the chamber, an uptake from the said shaft, electrodes in said chamber, carriages carrying said electrodes, and rails on which the carriages are movable, and a source of electricity connected to the rails said electrodes, carriages and rails being electrically connected together. 85 90 95

2. An electric furnace comprising a reaction chamber, a shaft communicating with said chamber and having a charge inlet, means for subjecting the material in the shaft to the heat lost by the radiation of the 100

reduction hearth, an uptake from the shaft, electrodes in the chamber, a refining chamber of carbon open to the air and communicating with said reaction chamber, said chamber having an outlet therein, and an auxiliary electrode adjacent said outlet, said refining chamber forming one of the poles.

In witness whereof I have signed this specification in the presence of two witnesses.

JEAN BOUNEAU.
